(57) **CLAIM**

The ornamental design for a net light, as shown and described.

DESCRIPTION

FIG. 1 is a front perspective view of a net light showing our new design;

FIG. 2 is a front elevation view thereof;

FIG. 3 is an enlarged view of the portion of the design identified with the numeral 3 in FIG. 2; and,

FIG. 4 is an enlarged view of the portion of the design identified with the numeral 4 in FIG. 2.

The net light is shown with a symbolic break in its length in FIGS. 1 and 2, and the appearance of any portion of the net light beyond the symbolic break forms no part of the claimed design. The broken lines in FIGS. 3 and 4 are for the purpose of illustrating the boundaries of the enlarged fragments marked 3 and 4 in FIG. 2 and form no part of the claimed design. The broken lines in FIG. 2 are for the purpose of illustrating the boundaries of the enlarged fragments shown in FIGS. 3 and 4 and form no part of the claimed design. The broken lines of the two outermost vertical elements and the bottom-most horizontal element in FIG. 1 and FIG. 2 form no part of the claimed design.
